CUSHION UNIT FORMING APPARATUS

Walter P. Cousino, Detroit, Mich., assignor to
Chrysler Corporation, Highland Park, Mich.,
a corporation of Delaware

Application June 16, 1937, Serial No. 148,617

15 Claims. (Cl. 153—77)

This invention relates to improved apparatus for manufacturing resilient cushion units for seats, mattresses, and the like.

More particularly, the invention pertains to apparatus for manufacturing cushion units of this character which include convoluted sheet-like resilient netting or other suitable resilient material.

One of the main objects of the invention is the provision of apparatus of this kind by which 10 elongated, sheet-like stock, such as netting comprising wire strands, can be economically and continuously brought to convoluted form and subsequently cut into units of desired length.

Another object of the invention is to provide 15 improved apparatus of this character by which successively adjacent sections of an elongated piece of sheet-like stock can be formed into convolutions of progressively varying height for producing tapering cushion units which vary in 20 height at selected portions.

A further object of the invention is to provide 25 selectively adjustable apparatus of this character by which may be formed cushion units having opposite sides that are parallel and substantially perpendicular to its height, two opposite sides which slope toward each other at inclinations to the heights of the unit, or one side which is perpendicular to the heights of the cushion and an opposite side inclined with respect thereto.

30 A still further object of the invention is the provision of apparatus of this kind which automatically repeats one tapered or non-tapered cushion unit forming operation after another.

Additional objects of the invention are to provide 35 improved means for crimping selected portions of the sheet-like stock in order that the same will be self-sustaining in contour; and to provide automatically operable crimping means of this character which is adapted to variably predetermine the angular relationship between portions 40 of the sheet-like material on opposite sides of the crimped portions thereof.

An illustrative embodiment of the invention is shown in the accompanying drawings, in which:

45 Fig. 1 is a fragmentary perspective view of one type of resilient cushion unit the improved apparatus is adapted to form.

Fig. 2 is a fragmentary perspective view of another type of resilient cushion unit the improved 50 apparatus is adapted to form.

Fig. 3 is a fragmentary perspective view of still another type of cushion unit the improved apparatus is adapted to form.

Fig. 4 is a vertical sectional view of a cushion 55 unit forming machine embodying the invention,

showing parts thereof removed to disclose the underlying structure.

Fig. 5 is a fragmentary vertical, transverse sectional view taken on the line 5—5 of Fig. 4.

Fig. 6 is a fragmentary, horizontal sectional view taken on the line 6—6 of Fig. 4.

Fig. 7 is a fragmentary horizontal sectional view taken on the line 7—7 of Fig. 4.

Fig. 8 is a vertical sectional view taken on the 10 line 8—8 of Fig. 4.

Fig. 9 is a transverse, vertical sectional view taken on line 9—9 of Fig. 7.

Fig. 10 is an end elevational view showing the machine illustrated in Fig. 4 as viewed from the 15 left of the latter figure.

Fig. 11 is an end elevational view showing the machine illustrated in Fig. 4 as viewed from the right of the latter figure.

Fig. 12 is a horizontal sectional view taken 20 on the line 12—12 of Fig. 10.

In Figs. 1 to 3 of the drawings are illustrated three forms of cushion units comprising convoluted sheet-like material which the improved forming apparatus is adapted to produce. In each of these forms the sheet-like material includes wire netting, generally designated by the numeral 10, having longitudinally extending strands or warp 11 comprising resilient wire similar to piano wire. The transverse strands or woof 12 may comprise ductile wire or any other suitable material including cord which may be relied upon to secure the warp in proper spaced relationship. The sheet-like stock of the foregoing nature is preferably dipped in a rubber-containing solution to provide a film of rubber-containing composition over or between the interstices of its entirety, or over selected space portions thereof. In the form illustrated in Fig. 1 the rubber film is designated by the numeral 13. In this figure the resilient cushion unit comprises 25 convolutions of uniformed heights and consequently the opposite side planes of the cushion unit are substantially parallel and perpendicular to the height of the unit.

In the form of the cushion unit illustrated in Fig. 2, the upper and lower rows of convolutions thereof progressively increase in height from left to right, as viewed in this figure in order to provide opposite side planes which converge and which are inclined with respect to the normal 50 height of the cushion. In Fig. 3 of the drawings is illustrated a cushion unit in which only the convolutions of one row of convolutions vary progressively in height, the convolutions of the other row being substantially uniform in height in 55

order to provide one side plane which is substantially normal to the heights of the convolutions and another side plane which is inclined with respect thereto.

5. Cushion units of the foregoing character are generally shown and described in Patents Nos. 2,094,041 and 2,094,074, both granted September 28, 1937 in the names of Lee and Tea, and Lee, Tea and Anderson, respectively.

10. The cushion unit forming machine illustrated in the drawings comprises, as shown in Fig. 4, a supporting frame structure generally designated by the numeral 14 having longitudinally spaced end plates 15 and 16, respectively, on 15 which upper and lower rolls 17 and 18, respectively are journaled. The roll 17 includes axially extending shaft portions 19 and 20 which are journaled in bearings 21 and 22, respectively, mounted in apertures formed in the side 20 plates 15 and 16, respectively. The roll 18 has axially extending shaft portions 23 and 24 journaled in bearings 25 and 26 mounted in apertures in the walls 15 and 16, respectively. The shaft portions 20 and 24 of the right ends of the 25 rolls 17 and 18, as viewed in Fig. 4, extend outwardly beyond the end plate 16 of the frame structure 14 and are provided with gears 27 and 28, respectively, having teeth permanently meshed together. The teeth of the lower gear 28 are 30 meshed with teeth of a drive pinion 29 carried by a shaft 30 by which the rolls are drivingly rotated in timed relationship with respect to each other.

The rolls 17 and 18 are provided with two sets of correspondingly arranged pairs of radially extending blades and vanes, the vanes of each roll having grooves in their outer extremity for receiving the end portions of respective corresponding blades of the other roll. In designating the blades and vanes of the respective rolls 17 and 40 18, lower case letters *a*, *b*, *c*, *d*, *e* and *f* have been applied to the blades of each of the rolls and capital letters *A*, *B*, *C*, *D*, *E* and *F* have been applied to the corresponding vanes with which the foregoing blades of each of the rolls cooperate. The folds or creases formed by the corresponding blades and vanes are designated by the 45 corresponding letters *a'* to *f'*, inclusive, in Fig. 1.

Each of the vanes *B* and *C* comprise a central plate 31 and side plate 32 adjacent the opposite 50 side surfaces thereof which are detachably secured to the center plate 31 by screws 33. The side plates 32 extend beyond the outer extremities of the center plate 31 in order to provide the above mentioned grooves at the outer extremities 55 of the vanes. Each vane *A* and *D* comprises a fixed center plate 34 having a fixed side plate secured adjacent one side surface thereof by a screw 35 and a movable side plate or jaw 36 disposed adjacent the opposite side surface of the 60 center plate 34 and confined between the latter side surface and a supporting wedge 37 carried by the roll. Formed in the supporting wedge 37 is a recess 38 in which is disposed a longitudinally extending expandable tube 39, preferably comprising rubber. The vanes *A* and *D* and associated clamping mechanism are substantially identical and therefore a description of one will serve for all. The left end of the tube 39, as viewed 65 in Fig. 4, is closed and the right end thereof is provided with a fluid medium inlet tube 40 which is connected to a fitting 41 carried by the roll 17, for example, and through which fluid may be supplied to the interior of the tube 39. The interior of the fitting 41 communicates with a 70 system of passages 42 leading from the roll

through the center of the shaft portion 20 thereof to the external end of this shaft portion. A fluid pressure supply line 43, connected with a source of fluid pressure (not shown), is communicatively connected with the external end portion of the 5 passage 42 of the shaft support 20. As illustrated in Fig. 4, a passage system 42 supplies fluid pressure to the expandable tubes 39 of the vanes *A* and *B* of each roll, respectively.

Provided in the fitting 41, associated with each 10 expandable tube 39, is valve mechanism for automatically charging and exhausting fluid medium from the interior of each flexible tube. This valve mechanism includes a valve member 44 having a stem 45 extending beyond the housing 15 of the fitting 41 and adapted to be engaged and operated by a cam plate 46 mounted on the end wall 16 of the supporting frame 14. As the roll 17, for example, rotates the cam plate urges the valve and valve stem leftwardly, as viewed in 20 Fig. 4, at desired angular positions of the roll in order to admit fluid medium from the passage system 42 to the inlet pipe 40. When the valve is in its inwardly pressed position, the exhaust port or groove 47 thereof is closed. A spring 48 25 bearing between the valve 44 and a shoulder in the interior of the casing of the fitting 41 normally urges the valve rightwardly, as viewed in Fig. 4, cutting off the supply of fluid medium to the yieldable tubes 39 and connecting the same 30 to atmosphere through the exhaust groove 47, when the cam plate will permit such rightward movement of the valve.

The fluid pressure medium system of each 35 roller is provided with similar valve control means to predetermine the periods of arcuate travels of the rollers during which the movable clamping jaws 36 of the vanes *A* and *D* are actuated. The movable jaws 36 are normally spread apart from the fixed jaws of the vanes *A* and *D* 40 by spring plates 49 disposed in recesses 50 formed in the sides of the central plates 34, as illustrated in Figs. 6 and 7.

In order to predetermine and, in some cases, vary the distances between selected fold edges 45 produced by the cooperating vane and blade members of the respective rolls 17 and 18, there are provided on each of the foregoing rolls radially extensible spacing members generally designated by the numeral 51, 52, 53 and 54 on the 50 upper roll 17, as viewed in Fig. 8, and 55, 56, 57 and 58 on the lower roll 18. These extensible spacing members are substantially identical in construction and therefore the description of one will serve for all. Each of the extensible members includes a central plate 59 mounted in a groove 60 formed in one of the rolls. Each plate 59 is somewhat shorter than the length of the roll on which it is mounted and extends substantially radially outwardly from the periphery 60 of the roll and is provided with a pair of slots 61 which are inclined with respect to the longitudinal axis of the roller. Radially slidably mounted on each plate 59 is an extensible member 62 of U-shaped cross section. Movement 65 of the U-shaped extensible member 62 is controlled by cross pins 63 extending through the slot 61 and having rollers 64 thereon engaging the edge portions of the slot 61 in order to maintain the outer rounded edge 65 of the extensible member 62 substantially parallel to the axis of the roll.

The extensible member 62 of each spacing means may be adjustably radially positioned by shifting them axially of the roll in order to bring 75

about a cam and follower action between the inclined slots 61 and rollers 64. All of the spacing members of both rolls, designated by the numerals 51 to 58, inclusive, may be simultaneously varied in accordance with and in timed relationship with respect to rotation of the rolls 17 and 18 by the apparatus illustrated in Figs. 4, 10 11 and 12. This apparatus comprises a plate 66 axially slidably mounted on each shaft 20 end portion 19 and 23 of each of the rolls 17 and 18, respectively. Inasmuch as the plates 66 of each of the rolls 17 and 18 are alike, a description of the plate 66 of the roll 18 will serve for both. Links 67 pivotally mounted at their 25 left ends, as viewed in Fig. 4, on the plate 66 extend between the sides of the U-shaped extensible members 62 and are pivotally attached thereto by a cross pin 68 at a location leftwardly of the left extremity 79 of the center plate 59. The plate 66 is yieldably urged leftwardly by coil 30 springs 80 disposed in bores 81 formed in the body portion of the roll 18 and which bear between the latter and the adjacent side face of the plate 66. The springs 80 urge the plate 66 and extensible members 62 leftwardly as viewed 35 in Fig. 4, thereby retaining the extensible members 62 in their retracted position. During rightward movement of the plate 66, the extensible members 62 are accordingly moved rightwardly and they are cammed outwardly by the slot and 40 roller connection between the extensible members and the center plate 59. In this manner, simultaneous movements of all of the extensible members 62 of the spacing means of each roll are 45 simultaneously adjusted.

The plates 66 of the rolls 17 and 18 are simultaneously and correspondingly actuated by spaced forks 82 carried by a shaft 83 which is journaled in bearings 84 mounted on the side plate 15 of the frame structure. One fork of the shaft 83 operates upon the plate 66 of each roll 17 and 18, respectively, through the medium of a ball bearing race ring 85 surrounding a hub portion on the plate 66, there being a series of ball bearings 86 interposed between the race ring 85 and the hub portion of the plate 66, as illustrated in Fig. 4.

The shaft 83 and forks 82 carried thereby are automatically actuated by control mechanism comprising a cam 87 and follower 88, shown in Fig. 10. The cam 87 is drivingly operated in timed relationship with respect to rotation of the rolls 17 and 18 by a train of gearing comprising a gear 89 fixed on the left end portion 23 of the shaft of the lower roll 18, having teeth meshed with an idler pinion 90 carried by an idler shaft 91 having a second idler pinion 92 provided with teeth meshed with a cam gear 93 journalled on the left end portion 19 of the shaft of the upper roll 17. The cam 87 is drivingly connected by a pin 94 with the cam gear 93, as illustrated in Fig. 4. The relative sizes of these gears and pinions may be so predetermined so as to cause one complete rotation of the cam 87 during a selected number of rotations of the rolls 17 and 18 corresponding to the number of rotations thereof required to produce one complete cushion unit.

The follower 88 comprises a lever having one end pivotally mounted at 95 on the frame structure of the apparatus and is provided with a plurality of holes 96 by virtue of which its effective length may be altered if desired. Pivotally attached to the follower 88 at a location intermediate its ends is an adjustable link 97 having

a bifurcated end portion 98 pivotally connected with a crank arm 99 fixed on the shaft 83 and by means of which the shaft 83 is rotated to actuate the forks 82 and the plates 66 with which they cooperate. The contour of the cam 87 5 predetermines the amount the extensible U-shaped member 62 of the variable spacing means 51 to 58 are extended outwardly during each rotation of the roll 17 and 18. After a predetermined number of rotations of the rolls 17 and 10 18 corresponding to the number of rotations required to produce a cushion of a selected dimension, the upper end of the follower, as viewed in Fig. 10, moves into the low point or notch 100 of the cam 87 at which point one complete cycle 15 of the operation of the apparatus is completed and the next cycle is ready to commence.

When the spacing means of both rolls 17 and 18 are varied in the foregoing manner during one complete cushion forming cycle of operation 20 of the apparatus, the height of both the upper and lower series of convolutions shown in Fig. 2 are successively varied to produce a cushion unit of wedge-shaped formation having upper and lower converging sides inclined with respect to 25 the central intermediate plane of the cushion. If desired, the plate 66 of either or both the upper and lower rolls 17 or 18 may be rendered inoperative or adjustably fixed in order to vary only the spacing means of one of the rolls or 30 35 so as not to vary the spacing means of either of the rolls during each cushion forming cycle thereof. In this case only one of the rows of convolutions, as shown in Fig. 3, is varied in height and as a result only one side face of the 35 cushion will be brought into inclined relationship with respect to a horizontal plane, for example. This may be accomplished by removing one or both of the set screws 105 by which the forks 82 are non-rotatably secured to the shaft 40 45 50 55 60 65 70 75 80 85 90 95 100 105 110 115 120 125 130 135 formation. The cushion unit may be embodied in a seat, mattress or similar structure, by enclosing it within suitable upholstery or fabric material. The apparatus is entirely automatic in its operation and is capable of high speed production of cushion units.

Although but several specific embodiments of the invention are herein shown and described, it will be understood that various changes in 10 the size, shape and arrangement of parts may be made without departing from the spirit of my invention.

What I claim is:

1. Apparatus for forming a cushion unit from 15 resilient sheet-like material comprising a pair of rolls between which said material is receivable, a plurality of spaced outwardly extending vane members on each roll having a channel in its outer extremity, and a plurality of blades on 20 each roll constructed and arranged to extend into the channel of a corresponding vane member on the other roll respectively during each complete rotation of said rolls for creasing said material 25 during passage thereof between said rolls at selected locations and in respectively opposite directions relative to the plane of said material respectively and for conditioning the latter to assume a self-sustaining convoluted contour.
2. Apparatus for forming a cushion unit from 30 resilient sheet-like material comprising a pair of rolls between which said material is receivable, a plurality of spaced outwardly extending vane members on each roll having a channel in its outer extremity, a plurality of blades on each roll 35 constructed and arranged to extend into the channel of a corresponding vane member on the other roll respectively during each complete rotation of said rolls for creasing said material 40 during passage thereof between said rolls at selected locations and in respectively opposite directions relative to the plane of said material respectively and for conditioning the latter to assume a self-sustaining convoluted contour, and 45 means on each of said rolls for selectively predetermining the distances between the locations on said material at which certain of said creases are formed.
3. Apparatus for forming a cushion unit from 50 resilient sheet-like material comprising a pair of rolls between which said material is receivable, a plurality of spaced outwardly extending vane members on each roll having a channel in its outer extremity, a plurality of blades on each 55 roll constructed and arranged to extend into the channel of a corresponding vane member on the other roll respectively during each complete rotation of said rolls for creasing said material 60 during passage thereof between said rolls at selected locations and in respectively opposite directions relative to the plane of said material respectively and for conditioning the latter to assume a self-sustaining convoluted contour, and automatically variable members operable in 65 timed relation to rotation of said rolls for varying the distance between locations on said sheet-like material at which certain of said creases are formed during convolutions forming cycles of said rolls.
4. Apparatus for forming a cushion unit from 70 resilient sheet-like material comprising a pair of rolls between which said material is receivable, a plurality of spaced outwardly extending vane members on each roll having a channel in its outer extremity, a plurality of blades on each roll 75

constructed and arranged to extend into the channel of a corresponding vane member on the other roll respectively during each complete rotation of said rolls for creasing said material during passage thereof between said rolls at selected 5 locations and in respectively opposite directions relative to the plane of said material respectively and for conditioning the latter to assume a self-sustaining convoluted contour, substantially radially shiftable spacing members on said rolls 10 for varying the distance between locations on said sheet-like material at which certain of said creases are formed, and apparatus for automatically varying the positions of said spacing members during operation of said rolls, said apparatus 15 being operable in timed relation to rotation of said rolls and so constructed and arranged as to progressively decrease the distance between certain of said locations during a selected number of convolution-forming cycles of operation 20 of said rolls.

5. Apparatus for forming from a strip of sheet-like resilient material a cushion unit comprising successive convolutions extending at opposite inclinations with respect to a plane intermediate 25 the opposite side planes of said unit including first and second rolls between which said strip is receivable, three successive coacting female and male creasing members on said first and second rolls respectively adapted to crease said strip 30 transversely of its length at longitudinally spaced locations and to fold adjacent panels thereof in one direction relative to the normal plane of said strip during passage thereof between said rolls for forming one of said convolutions of said unit, 35 and three consecutive male and female creasing members on said first and second rolls respectively adapted to crease said strip transversely of its length at longitudinally spaced locations and to fold adjacent panels thereof in an opposite direction relative to the normal plane of said strip for forming the next successive convolution 40 of said unit.

6. Apparatus for forming from a strip of sheet-like resilient material a cushion unit comprising 45 successive convolutions extending at opposite inclinations with respect to a plane intermediate the opposite side planes of said unit including first and second rolls between which said strip is receivable, three successive coacting female and male creasing members on said first and second rolls respectively adapted to crease said strip 50 transversely of its length at longitudinally spaced locations and to fold adjacent panels thereof in one direction relative to the normal plane of said strip during passage thereof between said rolls for forming one of said convolutions of said unit, 55 and three consecutive male and female creasing members on said first and second rolls respectively adapted to crease said strip transversely of its length at longitudinally spaced locations and to fold adjacent panels thereof in an opposite direction relative to the normal plane of said strip for forming the next successive convolution 60 of said unit, said rolls having duplicate sets of 65 said creasing members disposed in said foregoing arrangement for forming four successive convolutions of said unit during each complete rotation of said rolls.

7. Apparatus for forming from a strip of sheet-like resilient material a cushion unit comprising 70 successive convolutions extending at opposite inclinations with respect to a plane intermediate the opposite side planes of said unit including first and second rolls between which said strip is 75

- receivable, three successive coacting female and male creasing members on said first and second rolls respectively adapted to crease said strip transversely of its length at longitudinally spaced 5 locations and to fold adjacent panels thereof in one direction relative to the normal plane of said strip during passage thereof between said rolls for forming one of said convolutions of said unit, three consecutive male and female creasing members 10 on said first and second rolls respectively adapted to crease said strip transversely of its length at longitudinally spaced locations and to fold adjacent panels thereof in an opposite direction relative to the normal plane of said strip for forming the next successive convolution of 15 said unit, and variable spacing members between certain of said creasing members for predetermining the distance between the creases formed thereby in said strip.
- 20 8. Apparatus for forming from a strip of sheet-like resilient material a cushion unit comprising successive convolutions extending at opposite inclinations with respect to a plane intermediate the opposite side planes of said unit including first and second rolls between which said strip is receivable, three successive coacting female and male creasing members on said first and second rolls respectively adapted to crease said strip transversely of its length at longitudinally spaced 25 locations and to fold adjacent panels thereof in one direction relative to the normal plane of said strip during passage thereof between said rolls for forming the next successive convolution of said unit, one of said female creasing members of one roll including relatively movable jaws between 30 which the associated male creasing member of the other roll and portions of said strip are receivable, means for automatically bringing said jaws toward each other when said latter male creasing member and portions of said strip are disposed 35 therebetween including a pneumatically expandible element, and actuating mechanism operable in timed relation with respect to rotation of said rolls for supplying a fluid pressure medium thereto.
- 35 9. Apparatus for forming from a strip of sheet-like resilient material a cushion unit comprising successive convolutions extending at opposite inclinations with respect to a plane intermediate the opposite side planes of said unit including first and second rolls between which said strip is receivable, three successive coacting female and male creasing members on said first and second rolls respectively adapted to crease said strip transversely of its length at longitudinally spaced 40 locations and to fold adjacent panels thereof in one direction relative to the normal plane of said strip during passage thereof between said rolls for forming the next successive convolution of said unit, variable spacing members between certain of said creasing members for predetermining the distance between the creases formed thereby in said strip, and control apparatus operable in 45 timed relationship with respect to rotation of said rolls for automatically varying the positions of said spacing members during each of a plurality of rotations of said rolls.
- 45 10. Apparatus for forming from a strip of sheet-like resilient material a cushion unit comprising successive convolutions extending at opposite inclinations with respect to a plane intermediate the opposite side planes of said unit including first and second rolls between which said strip is receivable, three successive coacting female and male creasing members on said first and second rolls respectively adapted to crease said strip transversely of its length at longitudinally spaced 50 locations and to fold adjacent panels thereof in one direction relative to the normal plane of said strip during passage thereof between said rolls for forming the next successive convolution of said unit, one of said female creasing members of one roll including relatively movable jaws between 55 which the associated male creasing member of the other roll and portions of said strip are receivable, and means for bringing said jaws toward each other when said blade and strip portions are therebetween in order to crimp the adjacent portions of said strip.
- 55 11. Apparatus for forming a cushion unit from resilient sheet-like material comprising a pair of rolls between which said material is receivable, a plurality of spaced outwardly extending vane members on each roll having a channel in its 60 outer extremity, a plurality of blades on each roll constructed and arranged to extend into the channel of a corresponding vane member on the other roll respectively during each complete rotation of said rolls for creasing said material during passage thereof between said rolls at selected locations and in selected directions relative to the plane of said material respectively and for conditioning the latter to assume a self-sustaining convoluted contour, one of said vane members of one roll including a pair of relatively 65 movable jaws between which a portion of a corresponding blade member of the other roll and portions of said strip are receivable, and means for bringing said jaws toward each other when said blade and strip portions are therebetween in order to crimp the adjacent portions of said strip.
- 65 12. Apparatus for forming from a strip of sheet-like resilient material a cushion unit comprising successive convolutions, including a support, first and second rolls rotatably supported by said support and adapted to receive said strip therebetween, three successive coacting female and male creasing members on said first and second rolls 70 respectively adapted to crease said strip transversely of its length at longitudinally spaced locations and to fold adjacent panels thereof in one direction relative to the normal plane of said strip during passage thereof between said rolls for forming the next successive convolution of said unit, one of said female creasing members of one roll including relatively movable jaws between 75 which the associated male creasing member of the other roll and portions of said strip are receivable, and means for bringing said jaws toward each other when said latter male creasing member and

fold adjacent panels thereof in an opposite direction relative to the normal plane of said strip for forming the next successive convolution of said unit, one of said female creasing members of 5 one roll including relatively movable jaws between which the associated male creasing member of the other roll and portions of said strip are receivable, a hydraulically expansible element carried by said latter roll and adapted to actuate said 10 relatively movable jaws, said latter roll having a passage for conveying fluid pressure to said expansible element, a valve element carried by said latter roll and adapted to control the passage of fluid pressure into and out of said expansible element, a cam member fixed to said support and adapted to adjust said valve element whereby the fluid pressure flow through said passage is controlled, said valve element and said cam member being operable in timed relation with respect to 15 20 25 the rotation of said rolls for adjusting said valve element so that fluid pressure is admitted from said passage to said expansible element to bring said jaws toward each other only when said latter male creasing member and portions of said strip are disposed therebetween.

13. Apparatus for forming from a strip of sheet-like resilient material a cushion unit comprising successive convolutions, including a support, first and second rolls rotatably supported by 30 said support and adapted to receive said strip therebetween, three successive coacting female and male creasing members on said first and second rolls respectively adapted to crease said strip transversely of its length at longitudinally spaced 35 locations and to fold adjacent panels thereof in one direction relative to the normal plane of said strip during passage thereof between said rolls for forming one of said convolutions of said unit, three consecutive male and female 40 creasing members on said first and second rolls respectively adapted to crease said strip transversely of its length at longitudinally spaced locations and to fold adjacent panels thereof in an opposite direction relative to the normal plane of 45 said strip for forming the next successive convolution of said unit, a plurality of longitudinally extending plate members fixed to said rolls between certain of said creasing members and extending substantially radially outwardly from the periphery of said rolls, each of said plate members having a pair of slots which are inclined with respect to the longitudinal axes of said rolls, extensible members of substantially U-shaped cross section each of which is slidably mounted 50 on one of said plate members and having cross pins extending into said slots, and means on said support for adjustably varying the location of said cross pins in said slots whereby the radial movement of each of said extensible members is 55 controlled for predetermining the distance between the creases in said strip which are formed by said latter creasing members.

14. Apparatus for forming from a strip of sheet-like resilient material a cushion unit comprising successive convolutions extending at opposite inclinations with respect to a plane intermediate the opposite side planes of said unit, including a support, first and second rolls having shaft end portions rotatably supported by said 60 support and adapted to receive said strip therebetween, three successive coacting female and male creasing members on said first and second rolls respectively adapted to crease said strip transversely of its length at longitudinally spaced 65 locations and to fold adjacent panels thereof in 70 75

one direction relative to the normal plane of said strip during passage thereof between said rolls for forming one of said convolutions of said unit, three consecutive male and female creasing members on said first and second rolls respectively adapted to crease said strip transversely of its length at longitudinally spaced locations and to fold adjacent panels thereof in an opposite direction relative to the normal plane of said strip for forming the next successive convolution of said unit, a plurality of longitudinally extending plate members fixed to said rolls between certain of said creasing members and extending substantially radially outwardly from the periphery of said rolls, each of said plate members having a pair of slots which are inclined with respect to the longitudinal axes of said rolls, extensible members of substantially U-shaped cross section each of which is slidably mounted on one of said plate members and having cross pins extending into said slots, a pair of plates each of which is axially slidably mounted on an adjacent shaft end portion of one of said rolls, links pivotally connected to the sides of said extensible members and to said plates, yieldable
